United States Patent Office.

GEORGE S. YINGLING AND SAMUEL F. POORMAN, OF TIFFIN, OHIO.

Letters Patent No. 64,824, dated May 14, 1867.

IMPROVED APPARATUS FOR MASHING AND COOLING IN BREWERIES.

The Schedule referred to in these Letters Patent and making part of the same.

TO ALL WHOM IT MAY CONCERN:

Be it known that we, GEORGE S. YINGLING and SAMUEL F. POORMAN, of Tiffin, in the county of Seneca, and in the State of Ohio, have invented certain new and useful improvements in Masher and Cooler for Brewers and Distillers; and do hereby declare that the following is a full, clear, and exact description thereof, reference being had to the accompanying drawings, and to the letters of reference marked thereon.

In the annexed drawings, making part of this specification, A represents a shaft, which stands in a vertical position in a mashing or cooling-tub used by distillers or brewers, having a bearing at its lower end in the bottom of the tub, and also one at its upper end, in a cross-bar which lies across the tub. B represents a cross-bar, which is passed through or into an opening which is cut at right angles to and through the shaft A, with its ends projecting on each side of said shaft nearly to the sides of the tub. C C represent a series of rounds, which are passed through the shaft A at right angles to it, and at a suitable distance apart. E represents a cross-bar, which is also passed through the shaft A at right angles to it, near its lower end, the opening which receives it being cut at right angles to the opening which receives the cross-bar B. At the lower end of the shaft A, and on each side of it, and also to the cross-bar E, are secured two stationary shovels or scrapers, F. To the lower ends of the two diagonal bars D are secured the shovels or scrapers G G. The bars D are provided with mortises in their upper ends, which fit over tenons on the ends of the upper cross-bar B, and are kept in position by pins which pass through the tenons at their ends. The lower ends of the bars are provided not only with the shovels G G, but on the opposite side from said shovels with a metallic clamp, H. The bars D run diagonally from the ends of bars B to the bars E, and are confined to said bars E by means of the clamps H. The shovels are made slightly concave on one side, and the shovels G connect to shovels F, making a close joint, as seen. This shaft A, with its devices for mashing and cooling, is revolved in the tub in which it is placed, and keeps the material within said tub thoroughly stirred.

Having thus fully described our invention, what we claim as new, and desire to secure by Letters Patent, is—

1. The use of the adjustable bars D D, provided at their lower ends with the shovels G G, which are used in connection with the shovels F F, as and for the purpose set forth.
2. The arrangement of the shaft A, with its bars B, E, and D, its rounds C C, and the shovels G and F, the several parts being constructed and used as and for the purpose herein specified.

In testimony that we claim the foregoing we have hereunto set our hands and seals this 12th day of March, 1867.

GEO. S. YINGLING,
SAMUEL F. POORMAN.
